UNITED STATES PATENT OFFICE.

JOHN MEREDITH MILLER, OF NEW YORK, N. Y.

COMBINED PEN AND PENCIL.

Application filed March 23, 1922. Serial No. 546,110.

To all whom it may concern:

Be it known that I, JOHN MEREDITH MILLER, a citizen of the United States, and a resident of 503 W. 140th St., New York 5 city, in the county of New York and State of New York, have invented a new and useful Improvement in Combined Pens and Pencils, of which the following is a specification.

10 The invention relates to combination fountain pen and mechanical pencil.

An object of the invention is to improve the construction, and as a result thereof the convenience and operation, of combination 15 pens and pencils, and a further object is to provide a combination self filling pen of the piston type and a mechanical pencil in which the pencil forms the piston for the pen, and in which the pencil may be locked 20 against movement with relation to the pen after the pen has been filled.

The invention is illustrated in the accompanying drawings, of which Fig. 1 is a central longitudinal sectional view of the 25 combined pen and pencil; Fig. 2 a side view of the pencil when removed from the pen; and Fig. 3 a transverse sectional view taken on the line III—III, Fig. 1.

Referring to the drawings, a tubular reservoir 1, preferably of cylindrical form, 30 constitutes the container or writing-fluid reservoir for a fountain pen 2 which is suitably attached to its outer end. The fountain pen may be protected by a suitable cap 3, which is preferably provided externally with a roughened file-like section 4 for sharpening the lead of the pencil. The pen is of the self-filling, piston type, the piston for which is at the end of a piston 35 rod in the form of a tube 5, which is also the casing of a mechanical pencil. Means are provided for locking the tube and reservoir against relative movements when the piston is moved to the inner end of the tubular reservoir so that there may not be an 40 accidental reverse movement of the pencil within the pen reservoir to forcibly eject the writing-fluid.

The piston at the end of tube 5 may take 45 the form of a head 6, surrounded by a suitable packing sleeve 7, which may be formed of cork. To lock the piston in its position adjacent to the inner end of reservoir 1, that is to say in the position indicated in Fig. 1, tube 5 is preferably provided with an ex-

ternal thread 8 adapted to be received by an internally formed thread on an inwardly enlarged portion 9 at the inner end of the reservoir. When the threads of the tube and reservoir engage each other the pen and 60 pencil are locked against relative axial movements and each lengthens the grip for the other. Leakage of writing-fluid between the piston and the inner end of the reservoir may be prevented by a packing ring 10 arranged between a flange 11, with which piston 6 is provided, and an inwardly extending flange formed by the enlargement 9 of the reservoir.

Various types of mechanical pencils may 70 be used to form the piston and piston rod for the pen. In the pencil shown herein casing 5 is interiorly threaded and has arranged in it a tube 12 provided with longitudinal slots through which there project 75 the sides of a follower 13. The inner end of tube 12 may be provided with an annular groove 20 adapted to be engaged by a split expandable ring 21 arranged in a recess 22 formed in the piston head 6. In 80 this way the end of tube 12 may be rotatably mounted in casing 5. Follower 13 is provided with serrations cooperating with the threads formed on the interior of tube 5 so that when this tube is rotated in a right 85 hand direction the follower will move toward the outer end of the pencil.

At the outer end of the pencil a tip 14 is attached to tube 12 by a left hand thread 15, the tip being provided with an opening 90 to receive a lead 16.

To retard the outward movement of a lead, a packing of elastic material is preferably arranged between the lead and the inner wall of the opening, in which the lead is 95 arranged. This packing may, and preferably does, take the form of an annular body 17 of cork or rubber, which is sufficiently elastic or compressible to permit the movement of a lead through it, but which 100 frictionally resists such movement of a lead sufficiently to prevent the lead from dropping out of a pencil.

A storage chamber for extra leads for the pencil is provided in the form of a sleeve 105 18 surrounding the pencil casing 5. This sleeve is provided with lead receiving chambers 19 adapted to be closed by the end of reservoir 1 when the sleeve is in its normal position upon casing 5, the casing being of 110

- smaller external diameter than reservoir 1. To hold sleeve 18 upon tube 5, such tube may be knurled or otherwise roughened as indicated in Fig. 2.
- 5 When it is desired to fill reservoir 1 of the fountain pen with writing-fluid, sleeve 18 is removed from tube 5, the tube is turned relatively to reservoir 1, so as to detach the threaded connection between the two, and 10 tube 5 is moved towards the fountain pen or outer end of the reservoir. Moving tube 5 in its opposite direction results in the filling of reservoir 1, writing-fluid being drawn in by the suction action of piston 6.
- 15 Tube 5 and reservoir 1 may then be rotated so that they become attached to each other through the threads 8 on tube 5, and thereafter storage reservoir 18 may be placed upon tube 5.
- 20 In causing follower 13 to move towards the point of the pencil to eject the lead, the left hand threaded connection 15 between tip 14 and casing 5 becomes somewhat tightened so that the turning of casing 5 to 25 move follower 13 inwardly will not loosen the threaded connection 15. However, when the follower reaches its extreme inner position, further turning of tip 14 will detach it from casing 5 so that a new lead may 30 be inserted from the inner end of tip 14. Tube 12 may be removed from casing 5 by pulling the tube outwardly with sufficient force to spread split ring 21 and thereby disengage groove 20 of tube 12 from this 35 ring. Such removal of tube 12 may be desirable to fix the pencil in case it does not function properly.
- According to the provisions of a patent 40 statute, I have described the principle and operation of my invention together with the preferred embodiment thereof. However, I desire to have it understood that, within the scope of the appended claims, my invention may be practiced by other forms of 45 construction than that particularly shown and described.
- I claim:
1. The combination of a tubular reservoir having a fountain pen at its outer end, a 50 tube provided with a head forming a piston movable through said reservoir to fill the reservoir with writing fluid, said tube forming the casing of a mechanical pencil, and means for locking said tube and reservoir 55 against relative movements when the piston end of the tube is adjacent to the inner end of the reservoir.
  2. The combination of a tubular reservoir having a fountain pen at its outer end, a 60 tube provided with a head forming a piston movable through said reservoir to fill the reservoir with writing fluid, said tube forming the casing of a mechanical pencil, the 65 inner end of said reservoir being interiorly threaded to receive external threads formed
- on said tube adjacent to the piston, whereby the tube and reservoir may be locked against relative movements when said piston is adjacent to the inner end of the reservoir.
3. The combination of a tubular reservoir 70 having a fountain pen at its outer end, and having an inwardly extending flange and interior threads at its inner end, a tube provided with a head forming a piston movable through said reservoir to fill the reservoir 75 with writing fluid, said tube forming the casing of a mechanical pencil and being provided with an exterior thread adjacent to said piston adapted to engage said interior threads on the reservoir, and a packing ring arranged between said flange and said piston.
4. The combination of a tubular reservoir 80 having a fountain pen at its outer end, a tube of smaller diameter than said reservoir provided with a head forming a piston movable through said reservoir to fill the reservoir with writing fluid, said tube forming the casing of a mechanical pencil, and a sleeve 85 of substantially the same outer diameter as said reservoir slidably mounted upon the portion of said tube projecting beyond the reservoir, said sleeve being provided with an open ended chamber to receive extra leads, the open end of the chamber being normally closed by the inner end of the reservoir.
5. The combination of a tubular reservoir 90 having a fountain pen at its outer end, and a mechanical pencil including a threadably advancing lead expeller, reciprocable in said reservoir and provided at its end with a piston whereby said pencil forms the piston and piston rod of a piston-type self-filling fountain pen.
6. The combination of a tubular ink reservoir 95 having a fountain pen at its outer end, and a mechanical pencil including a rotatable tip and threadably advancing lead expeller operatively connected to the tip, said pencil being movable in said reservoir and being provided with means for filling the reservoir by relative movement between reservoir and pencil.
7. The combination of a tubular reservoir 105 having a fountain pen at its outer end, a tube of smaller outer diameter than that of said reservoir secured to the inner end of said reservoir and forming an extension thereof for a longer grip, said tube being the casing of a mechanical pencil and being provided with an open ended chamber to receive extra leads, the open end of said chamber being normally closed by the inner end of said reservoir.
- In testimony whereof, I sign my name.
- JOHN MEREDITH MILLER.
